UNITED STATES PATENT OFFICE.

FRANK R. RUSH, OF AKELEY, PENNSYLVANIA.

RAIL-JOINT.

954,347.

Specification of Letters Patent.

Patented Apr. 5, 1910.

Application filed May 21, 1909. Serial No. 487,563.

To all whom it may concern:

Be it known that I, FRANK R. RUSH, a citizen of the United States, residing at Akeley, in the county of Warren and State of Pennsylvania, have invented new and useful Improvements in Rail-Joints, of which the following is a specification.

This invention relates to improvements in rail joints, the object of the invention being 10 to provide coöperating splicing or coupling devices adapted to be secured to the meeting ends of the rails and adjacent ties in such a manner as to effectually brace and support the rails against either lateral or 15 longitudinal movement, forming a joint construction which will prevent independent movement of the rails except to the slight extent for expansion and contraction, and which at the same time admits of the ready 20 disassociation of the parts for repairs or the substitution of new rails or elements of the track structure.

The invention consists of the features of construction, combination and arrangement 25 of parts hereinafter fully described and claimed, reference being had to the accompanying drawing, in which:—

Figure 1 is a side elevation of the meeting ends of two rails connected by my improved joint. Fig. 2 is a bottom plan view 30 of the same. Fig. 3 is a vertical transverse section on line 3—3 of Fig. 1. Fig. 4 is a perspective view of one of the coupling devices.

35 Referring to the drawing, the numerals 1 and 2 represent the meeting ends of adjoining rails, and 3 supporting ties arranged below the rails on opposite sides of the line of the joint.

40 The improved joint fastening comprises splicing or coupling members 4 and 5, which are similar in construction so that a description of one will suffice for both. Each coupling member is of a length to extend a 45 proper distance beyond the line of the joint, and embodies a vertical fish-plate 6 provided at its upper and lower edges with shoulders 7 and 8 to bear against the adjacent side of the web of the rail at the points 50 of junction of the latter with the head and base flange of the rail. The plate 6 is also provided with the usual openings 8' for the passage of the bolts 9 for fastening the rails and coupling members together.

55 From the lower edge of the plate 6 extends a flange 10 which projects laterally outward

and is inclined to rest upon the upper surface of the adjacent flange of the rail base and is adapted to be engaged at its outer edge adjacent to its respective ends by the 60 heads of spikes or similar fastening devices which are driven into the ties 3 to secure the coupling member thereto. By means of the bolts and spikes the coupling members are firmly fastened to the rails and to the 65 ties to prevent relative lateral movement of the rails or relative longitudinal movement thereof except to the slight extent required for contraction and expansion.

Projecting inwardly from the outer edge 70 of the flange 10 is a base plate 12, which is of a length equal to the distance between the inner faces of the ties 3 and of a width somewhat less than one half the width of the base of the rail, so that the ends of the 75 rails are exposed beyond said plates to rest squarely upon the upper surfaces of the ties, while the plates 12 of the respective coupling members project beneath the rails between the ties and thus stay and support the 80 rails from depression. The plates 12 further have their end portions bearing against the adjacent sides of the ties to prevent any possibility of longitudinal shifting of the rails and coupling members, thus avoiding 85 the tendency of the rails to "creep".

In order to secure a firm connection between the base plates 12 and the rail, said plates are each formed with an opening 13 registering with a corresponding opening 14 90 in the overhanging portion of the coating flange 10. Through these openings extend clamping bolts 15 whose heads rest upon the upper surfaces of the flanges and whose lower ends project below the plates 12 and 95 are provided with securing nuts 16. These bolts project downward between the meeting ends of the adjacent flanges of the rails, which portions of the rails are formed with registering grooves or recesses 17 receiving 100 the shanks of the bolts. When the parts are assembled, the bolts are passed downward through the openings and recesses and the nut 16 applied and drawn tight to move the parts 10 and 12 relatively toward one another so as to cause them to firmly and securely clamp the base flanges of the rails and to thereby add to the security of the 105 joint.

From the foregoing description, taken in 110 connection with the drawing, it will be seen that the invention provides a rail joint

which is not only simple of construction, but firmly ties the rail and forms a secure support therefor at the joint, as well as preventing either vertical, lateral or longitudinal movement of the rail, and that withal the parts of the joint may be readily and quickly disassembled for convenience in making repairs or substituting new rails for those worn by continuous service.

Having thus fully described the invention, what is claimed as new is:—

The combination with the meeting ends of rails, of supporting ties for the rails arranged adjacent such ends, coupling members embodying fish plates extending across the meeting ends of the rails and bearing against the opposite sides of the webs of the rails, said plates being provided with outwardly extending base flanges resting on the base flanges of the rails, and the upper surfaces of the ties, said flanges being co-extensive in length with the fish plates and having base plates projecting inwardly therefrom and beneath the rails between the ties and bearing at their ends against the

opposing faces of the ties, the end portions of the base flanges of the rails being provided with mating grooves or recesses and the flanges and base plates of the coupling members with openings registering with said grooves, rounded longitudinal bearing ribs on the upper and lower edges of the inner faces of the fish plates to bear upon the webs of the rails adjacent the heads and base flanges thereof, fastening members engaging the outer edges of the base flanges of the coupling members and securing the same to the ties, and fastening bolts passing through said grooves in the ends of the rails and holes in the flanges and base plates of the coupling members and operating to draw said flanges and base plates together to clamp said base flanges to the rails.

In testimony whereof I affix my signature in presence of two witnesses.

FRANK R. RUSH.
